UNITED STATES PATENT OFFICE

HOWARD T. HALLOWELL AND FRANK BENNETT, OF JENKINTOWN, PENNSYLVANIA, ASSIGNORS TO STANDARD PRESSED STEEL CO., OF JENKINTOWN, PENNSYLVANIA, A CORPORATION OF PENNSYLVANIA

BENCH

Application filed December 12, 1929. Serial No. 413,528.

Our invention relates to certain improvements in benches, particularly those used in locker-rooms or shops where they are subjected to rough usage.

5 The object of our invention is to make a bench of sheet metal bent into shape, so that while it will be very substantial, it will be comparatively light.

In the accompanying drawings:

10 Fig. 1 is a perspective view of our improved bench;

Fig. 2 is a transverse sectional view;

Fig. 3 is a longitudinal sectional view of one end of the bench;

15 Fig. 4 is a sectional plan view on the line 4—4, Fig. 2; and

Fig. 5 is a perspective view of one of the feet secured to the bottom of the legs of the bench.

20 Referring to the drawings, 1 is the top of the bench made in a single piece of sheet metal, bent at each side to form flanges 2, which are turned at 3 some distance from the edge of the bench, and a deep flange 4 depends from the inturned portion, as clearly shown in Fig. 2. This construction provides 25 the full length of the bench.

Secured to the inturned flanges are the 30 legs 5, located some distance from each end of the bench and arranged at a slight angle as shown in Fig. 3. These legs are flanged at each side 6, and the ends of the flanges are turned inwards as at 7, so as to make the 35 legs very substantial and yet comparatively light.

Bolts, rivets or other fastenings 8 extend through the flanges 6 of the legs and through the flange 4 of the top section, firmly securing 40 the two parts together. The part 9 of the body portion of each leg 5 extends beyond the flange 6 and rests against the underside of the top of the bench and is secured thereto by a rivet 10, or other fastening.

We preferably locate feet 11 at the bottom of the legs 5, and these feet are formed by U-shape pieces of metal, which are forced into the channel of each leg, as shown in Fig. 50 4, and held in place by friction, but in some

instances they may be welded to the legs.

In Fig. 6 we have shown a bench having a wooden top and metallic legs and side members. The legs 5a are shown in the same manner as the legs shown in Figs. 2 and 3, 55 and are secured to the angle beams 4a, which extend the full length of the beams and are beveled at each end as shown in Fig. 7. The upper flanges 4b of the angle beams are secured to a top 1a of wood or other suitable material, by screws 10a. The portion 9a of the body of the leg is bent in the same manner as the portion 9 of the leg 5, and is secured to the upper flanges 4b of the angle beams 4a, as clearly shown in Figs. 6 and 7. 60

We claim:

1. The combination in a bench, of a one-piece top section made of sheet metal, bent at each side to form flanges and bent inwards and then downwards to form a deep flange some distance from the edge of the top section; legs having flanges at each side with inturned edges, a portion of each leg being bent to rest against the underside of the top; means securing the said portion to the top of the bench; and means securing the flanges of the legs to the flanges of the top section. 70

2. The combination in a bench, of a one-piece top section made of sheet metal, bent at each side to form flanges, said flanges being bent inwards and then downwards to form deep supplemental flanges some distance from the edge of the top section; and sheet metal legs extending to the under side 75 of the top section and secured thereto, and also secured to the depending supplemental flanges of the said top section. 80

HOWARD T. HALLOWELL.
